ONE SHOT MULTIVIBRATOR

Robert B. Trousdale, Webster, N. Y., assignor, by mesne assignments, to General Dynamics Corporation, a corporation of Delaware

Application August 27, 1952, Serial No. 306,691

8 Claims. (Cl. 250—27)

The present invention relates to multivibrators and more particularly to a one-shot multivibrator employing gas tubes or tubes of the type including an ionizable medium. This application is a continuation-in-part of my co-pending application Serial No. 140,927, filed on January 27, 1950 and assigned to the same assignee as the present invention.

Multivibrators have come into extensive use in recent years as a source of square waves, as an electronic switch, and for other purposes. Many times it is desirable to cause an electronic switching operation or the like in response to the receipt of a single pulse after which it is desired for the circuit to be restored to its original quiescent condition until another pulse is received. It would be desirable to provide an arrangement in which an extremely high power output can be obtained in response to the receipt of each trigger pulse and in which the electronic circuit may readily be adapted for inverter operation or the like. Such an arrangement is particularly useful as a high power signal source for the ringing facilities, harmonic or otherwise, of an automatic telephone system.

Accordingly, it is an object of the present invention to provide a new and improved one-shot multivibrator.

It is another object of the present invention to provide an improved arrangement for initiating a cyclic operation upon receipt of a single trigger pulse in connection with a pair of vapor electric discharge valves.

It is a further object of the present invention to provide a one-shot multivibrator employing gas tubes in which an extremely high power output can be obtained.

Further objects and advantages of the present invention will become apparent as the following description proceeds and the features of novelty which characterize the invention will be pointed out with particularity in the claims annexed to and forming a part of this specification.

For a better understanding of the present invention reference may be had to the accompanying drawing in which the single figure is a schematic diagram of one embodiment of the present invention.

The present invention contemplates the employment of a pair of gas or so-called vapor electric discharge valves of the thyratron type connected into a circuit which is triggered in response to the receipt of a single pulse and which immediately shuts itself off, depending upon the time constant of the circuit, so as to reach and remain in a quiescent condition until another pulse is received.

Referring now to the drawing, there is illustrated an electronic discharge valve 10 which serves to control the supply energy from a source of B+ potential 11 to a utilization circuit generally designated at 12. Effectively, electronic discharge valve 10 acts as an electronic switch so that when rendered conductive, it supplies the full potential of the high power B+ source 11 to the utilization circuit 12, except for the small voltage drop through the valve 10 which is probably of the order of 10 volts or the like. Electronic discharge valve 10 is illustrated as

2

of the type containing an ionizable medium such as a gas or a vapor which is characterized by the fact that once rendered conductive by the control electrode, the valve remains conductive until the anode-to-cathode voltage is reversed or the anode circuit is interrupted. As illustrated, electronic discharge valve 10 comprises an anode 13, a cathode 14, a control electrode or grid 15 and a shield grid 16. The cathode 14 has its cathode terminal 17 connected to ground indicated at 18 through a suitable load resistor 19. When electron discharge valve 10 is rendered conductive, substantially the full potential of the source 11 except for the small potential drop through the valve 10 appears across the load resistor 19 and is supplied to the utilization circuit 12 as indicated. The shield grid 16 is connected to the cathode 14 in the conventional manner.

For the purpose of controlling the discharge through electron discharge valve 10, the control electrode 15 is connected to a source of input signal generally designated at 20 through a suitable coupling capacitor 21. A negative biasing potential from the source generally designated at 22 is supplied to the control electrode 15 through a current limiting resistor 23. The magnitude of the negative potential of the source 22 is controlled so as to maintain electron discharge valve 10 non-conductive under normal conditions. Upon the receipt of a signal pulse in the form of a positive pulse as indicated in the single figure of the drawing, the potential of the control electrode 15 is momentarily raised to a sufficiently great extent as to render electron discharge valve 10 conductive whereupon the negative biasing potential from the source 22 is incapable of terminating the conductive operation of the valve 10 even though no further signal pulse is received. With the arrangement described thus far, therefore, electron discharge valve 10 effectively comprises an electronic switch for supplying potential to the utilization circuit 12 in response to the receipt of a single positive pulse from the input signal source 20. Without more, however, the electron discharge valve 10 will remain conductive once it is rendered conductive unless the source of anode potential is effectively removed.

For the purpose of terminating the conducting characteristic of electron discharge valve 10 once it has been rendered conductive, there is provided a second electron discharge valve 25 also of the vapor discharge type and preferably identical with the electron discharge valve 10. As illustrated, electron discharge valve 25 comprises an anode 26, a cathode 27, a control electrode or grid 28 and a shield grid 29. To prevent electron discharge valve 25 from being conductive except substantially during the time that electron discharge valve 10 is conductive the anode 26 is connected to the cathode terminal 17, which is also the ungrounded terminal of the load resistor 19, through a suitable current limiting resistor 30. Effectively, therefore, the anode 26 is connected to the cathode 14 so that electron discharge valves 10 and 25 are arranged with their plate circuits in series circuit arrangement. The cathode 27 is connected to ground 31 through a suitable cathode resistor 32.

A suitable capacitor 33 for use as a temporary source of high plate currents through the tube 25 is connected between the plate 26 and ground. The shield grid 29 of the electron discharge valve 25 is connected to a suitable source of potential designated as negative potential source 34 through a current limiting resistor 35. The control electrode 28 of electron discharge valve 25 is connected to the load resistor terminal 17 through a suitable timing resistor 37 and to ground designated at 38 through a suitable timing condenser 39. With this arrangement it will be apparent that when electron discharge valve 10 is rendered conductive a charging circuit for capacitor 33 through resistor 37 is provided and the

charging time for condenser 39 is dependent upon its capacitance and the resistance of the resistor 37. The one-shot multivibrator circuit is completed by the addition of a capacitor 40 interconnecting the cathode 27 of electron discharge valve 25 with the load resistor terminal 17. This capacitor 40, as will become apparent from the following description, effectively is an arc extinguishing capacitor for extinguishing the discharge through electron discharge valve 10.

When no signal is supplied from the input 20 through the coupling capacitor 21, electron discharge valves 10 and 25 are non-conducting by virtue of the negative bias applied to the control electrode 15 from source 22 and the further fact that electron discharge valve 25 cannot be rendered conductive without electron discharge valve 10 having first been rendered conductive. Under these conditions the capacitor 33 is discharged through resistors 30 and 19, the capacitor 39 is discharged through the resistors 37 and 19, and the capacitor 40 is discharged through the resistors 32 and 19. Moreover, under these conditions the potential at terminal 17 of load resistor 19 is zero and consequently no potential is supplied to the utilization circuit 12. Upon the receipt of a signal such, for example, as a positive pulse from the input 20, the control electrode 15 is momentarily rendered sufficiently positive to cause electron discharge valve 10 to fire, whereby current flows through the load resistor 19 and substantially the entire potential of the source 11 is supplied to the utilization circuit 12. This potential is also supplied to the plate circuit of electron discharge valve 25 through the resistor 30, but by virtue of the negative biasing potential on the shield grid 29 electron discharge valve 25 remains nonconductive. The drop across load resistor 19 applies a potential across the timing circuit comprising resistor 37 and capacitor 39 which in turn causes capacitor 39 to charge to a sufficiently high potential which is applied to the control electrode 28 to render electron discharge valve 25 conductive, whereupon current flows through resistors 30 and 32 in the plate circuit of valve 25.

Capacitor 33 is charged through the resistor 30 to the potential of terminal 17 as soon as the valve 10 is fired. Accordingly, when the valve 25 is fired in the manner described above, the capacitor 33 acts as a temporary source of plate potential for the valve 25 and current flows over a path which includes the capacitor 33, the space current path of the valve 25, the capacitor 40 and the resistor 19 to the grounded terminal of the capacitor 33. This additional current flow through the resistor 19 raises the potential of the terminal 17 by an amount sufficient to extinguish the valve 10 by reversing the anode-cathode potential impressed thereon. In this connection it will be understood that when the valve 25 fires the potential drop through the valve 25 is relatively small and the potential across the capacitor 33 cannot be changed instantaneously so that substantially the full anode potential on the valve 25 is impressed upon the resistor 19 the instant the valve 25 fires. Electron discharge valve 25 will continue to conduct current until capacitor 33, which has been charged, discharges, which is only for a very short time and immediately capacitors 39 and 40 will discharge through resistors 37, 19 and 32, 19 respectively. The entire circuit is thereby restored to its initial condition and will remain so until a new trigger pulse is received.

Preferably electron discharge valves 10 and 25 are hot cathode type valves whereby it is possible to obtain an extremely high power output. Furthermore, the circuit may readily be adapted for inverter operation, particularly if arranged in a push-pull configuration.

While it will be apparent that the impedance values of the several circuit elements of the above-described system may be varied within wide limits in accordance with the particular requirements and desired characteristics of the system, the following constants for the control

circuit of the present invention have been found to be satisfactory for a particular installation:

Condenser 21	.....	.0001 microfarad.
Condenser 33	.....	.01 microfarad.
Condenser 39	.....	.1 microfarad.
Condenser 40	.....	.01 microfarad.
Electron discharge valve 10	.....	5696 (R. C. A.) type.
Electron discharge valve 25	.....	5696 (R. C. A.) type.
Resistor 19	.....	100,000 ohms.
Resistor 23	.....	1 megohm.
Resistor 30	.....	1 megohm.
Resistor 32	.....	10,000 ohms.
Resistor 35	.....	1 megohm.
Resistor 37	.....	2.2 megohms.

The value of the resistance of resistor 37 and the capacitance of capacitor 39 may be varied in order to vary the length of time which elapses between firing of electron discharge tube 10 and firing of electron discharge valve 25. In the event that the multivibrator described is used as a source of square waves, the time delay provided by the timing circuit will control the width of each half cycle of the square wave. It will be understood that the present invention also lends itself to use as an electronic switch for producing a gating voltage.

While there has been illustrated and described a particular embodiment of the present invention, it will be understood that various changes and modifications will occur to those skilled in the art. It is aimed in the appended claims to cover all such changes and modifications as fall within the true spirit and scope of the present invention.

What is claimed as new and desired to be secured by Letters Patent of the United States is:

1. In combination, a potential supply circuit, a utilization circuit, an electronic switch comprising a first electron discharge valve of the gas type for connecting said supply circuit to said utilization circuit, said valve having a control electrode, a signal source connected to said control electrode, the receipt of a predetermined signal from said signal source rendering said electronic switch effective to interconnect said supply and utilization circuits, a second electron discharge valve of the gas type, means for connecting the plate of said second valve to the cathode of said first valve, means including a capacitor for firing said second valve, and means including said connecting means for extinguishing the discharge through said first valve in response to the discharge through said second valve, the flow of current through said second valve being immediately terminated following extinguishment of the discharge through said first valve due to automatic removal of plate potential therefrom.

2. A gas tube one-shot multivibrator comprising a potential supply circuit, a utilization circuit, an electronic switch comprising a first electron discharge valve of the gas type for connecting said supply circuit to said utilization circuit, said valve having a control electrode, a signal source connected to said control electrode, the receipt of a predetermined signal from said signal source rendering said electronic switch effective to interconnect said supply and utilization circuits, a second electron discharge valve of the gas type, means for connecting the plate of said second valve to the cathode of said first valve, a cathode resistor in circuit with said second valve, a capacitor connected between the cathode of said first valve and the cathode of said second valve so as to be charged through said cathode resistor upon firing of said first valve, and means for momentarily producing a relatively high potential across said cathode resistor upon firing of said second valve whereby the sum of the potentials across said capacitor and cathode resistor causes extinguishment of the discharge through said first valve.

3. In combination, a source of potential, a load impedance, an electron discharge valve having an anode, a

cathode and a control electrode interconnecting said source and said load impedance, a signal source connected to said control electrode for rendering said electron discharge valve conductive, a second electron discharge valve having its plate circuit connected in parallel with said load impedance, an anode resistor and a cathode resistor included in said plate circuit, each of said electron discharge valves being of the type containing an ionizable medium, a capacitor, a charging circuit for said capacitor including said cathode resistor, means for connecting said charging circuit in parallel with said load impedance, and a capacitor effectively shunting said anode resistor to provide a momentary low impedance path through said second electron discharge valve following firing of said first valve whereby the potential across said charging circuit is momentarily raised sufficiently to extinguish the discharge through said first valve.

4. A one-shot multivibrator comprising a potential supply circuit, a utilization circuit, an electronic switch comprising a first electron discharge valve for connecting said supply circuit to said utilization circuit, said valve having a control electrode, a signal source connected to said control electrode, the receipt of a predetermined signal from said signal source rendering said electronic switch effective to interconnect said supply and utilization circuits, a second electron discharge valve, means for connecting the plate of said second valve to the cathode of said first valve, a cathode resistor in circuit with said second valve, a capacitor connected between the cathode of said first valve and the cathode of said second valve so as to be charged through said cathode resistor upon firing of said first valve, and means comprising a capacitive impedance in the plate circuit of said second valve for causing extinguishment of the discharge through said first valve upon firing of said second valve.

5. A gas tube one-shot multivibrator comprising a potential supply circuit, a utilization circuit, an electronic switch comprising a first electron discharge valve of the gas type for connecting said supply circuit to said utilization circuit, said valve having a control electrode, a signal source connected to said control electrode, the receipt of a predetermined signal from said signal source rendering said electronic switch effective to interconnect said supply and utilization circuits, a second electron discharge valve of the gas type, means for connecting the plate of said second valve to the cathode of said first valve, a cathode resistor in circuit with said second valve, a capacitor connected between the cathode of said first valve and the cathode of said second valve so as to be charged through said cathode resistor upon firing of said first valve, time delay means for firing said second valve a predetermined time after firing of said first valve, and means for momentarily producing a relatively high potential across said cathode resistor upon firing of said second valve whereby the sum of the potentials across said capacitor and cathode resistor causes extinguishment of the discharge through said first valve.

6. In combination, a source of potential, a load impedance, an electron discharge valve having an anode, a cathode and a control electrode interconnecting said source and said load impedance, a signal source connected to said control electrode for rendering said elec-

tron discharge valve conductive, a second electron discharge valve having its plate circuit connected in parallel with said load impedance, a cathode resistor for said second discharge valve included in said plate circuit, each of said electron discharge valves being of the type containing an ionizable medium, a capacitor, a charging circuit for said capacitor including said cathode resistor, means for connecting said charging circuit in parallel with said load impedance, and means responsive to firing of said second valve for causing the potential across said charging circuit to be raised sufficiently to extinguish the discharge through said first valve.

7. In combination, a source of potential, a load impedance, an electron discharge valve having an anode, a cathode and a control electrode interconnecting said source and said load impedance, a signal source connected to said control electrode for rendering said electron discharge valve conductive, a second electron discharge valve having its plate circuit connected in parallel with said load impedance, a cathode resistor for said second discharge valve included in said plate circuit, a capacitor, a charging circuit for said capacitor including said cathode resistor, means for connecting said charging circuit in parallel with said load impedance, time delay means including a capacitor paralleling said load impedance for controlling the firing of said second valve a predetermined time after firing of said first valve, and means responsive to the potential across said charging circuit following discharge through said second valve for extinguishing the discharge through said first valve.

8. In combination, a source of potential, a load impedance, a first electron discharge valve having an anode, a cathode and a control electrode interconnecting said source and said load impedance, a signal source connected to said control electrode for rendering said first electron discharge valve conductive, a second electron discharge valve having its plate circuit connected in parallel with said load impedance, a cathode resistor for said second discharge valve included in said plate circuit, each of said electron discharge valves being of the type containing an ionizable medium, a capacitor connected between the cathode of said first valve and the cathode of said second valve so as to be charged through said cathode resistor upon firing of said first valve, and time delay means for firing said second valve a predetermined time after firing of said first valve so that the flow of current through said second tube produces a relatively high potential across said cathode resistor, the sum of the potentials across said cathode resistor and said capacitor being sufficient to cause extinguishment of the discharge through said first valve.
